UNITED STATES PATENT OFFICE.

EDMUND P. KINNE, OF ALLIANCE, OHIO, ASSIGNOR TO AMERICAN STEEL FOUNDRIES,
OF CHICAGO, ILLINOIS, A CORPORATION OF NEW JERSEY.

RADIAL-MOTION OPERATING-LEVER.

1,103,916.

Specification of Letters Patent.

Patented Sept. 1, 1914.

Application filed October 18, 1911. Serial No. 354,243.

To all whom it may concern:

Be it known that I, EDMUND P. KINNE, a citizen of the United States, residing at Alliance, in the county of Stark and State of Ohio, have invented certain new and useful Improvements in Radial-Motion Operating-Levers, of which the following is a specification.

My invention relates to car couplers and has particular reference to novel operating levers for use in connection therewith.

Many railroads favor the use of bottom operated car couplers, that is, couplers which shall have their tops closed to prevent the entrance of snow or dirt, which would impede the operation of the coupler.

In view of the fact that the law requires that means shall be provided whereby couplers may be operated without the necessity of the workman entering between the cars, levers are extended to the sides of the cars these levers being connected to the lock-operating mechanism. The disadvantage in this construction lies in the fact that in rounding curves or entering sidings, the coupler must shift radially and that therefore the operating parts must likewise shift. If these parts become caught or work with difficulty, there is likelihood of the lock being operated and the coupler knuckle released, with the result that the train is parted, sometimes with serious accidents accruing. I am aware that many forms of locking operating levers have been suggested with the idea in view of avoiding this contingency. I have, however, in the present construction suggested a form which is not dependent on the possibility of any of the parts sticking or becoming bent or out of service. I have moved the operating lever back from the coupler head to a point close to the pivotal point of the coupler in turning. In this way the radial motion of the coupler will have practically no effect upon the operating lever, the lever being so close to the pivotal point of the coupler. Furthermore, another object is gained in that the operating lever or rod is placed under the car and back away from danger of being damaged during ordinary coupling or uncoupling operations.

Among the objects of my invention therefore, are first, to provide a coupler operating lever which shall be substantially independent of the radial motion of the couplers and

second, to so place the operating lever as to be out of danger of injury.

My invention will be more readily understood by reference to the accompanying drawings, wherein,

Figure 1 is an end elevation of a fragment of a freight car showing a coupler in place, the coupler having my novel operating lever associated therewith; Fig. 2 is a bottom plan of the same construction; Fig. 3 is a side elevation thereof; Fig. 4 is a modification, the form being the same as that of Fig. 3 except that an I-bolt connection is used in order to give still further flexibility; Fig. 5 is a front view of the application of my novel operating rod to a passenger car, in which case operating levers extend to both sides of the car; Fig. 6 is a side view of the construction shown in Fig. 5; Fig. 7 is a side elevation of a still further modification showing the application of the operating lever to a coupler arranged for wide radial movement; and Fig. 8 is a plan view of the construction of Fig. 7.

Referring more particularly to the drawings it will be seen that to a car 10 is secured draft sills 11, between which is mounted the draft rigging 12 and shank 13 of a coupler 14. The coupler may be of any particular design, the one shown herein having a lock operating lever 15 pivoted at 16 to a portion of the coupler head and provided with a weighted end 17 seated within a pocket in the coupler. Passing through an opening in the lever 15, is the hooked end 18 of a rod 19, the rod having a loop 20 near the rear end thereof. The rear end of said rod is carried by a bracket 21, secured to one of the draft sills 11. Secured on the loop 20 is an operating rod 22, having a hand-hold 23 at the outer end. The outer end is passed through a bracket 24, which is secured to the car body 10. It will be seen that the hook 18, after passing through the opening in the lever 15, is fulcrumed or rests against a portion of the lever 15 at a point below the opening therethrough. Therefore when the rod 22 is pulled, the lever 15 is turned on its pivot and the lock of the coupler raised. The weight of the parts, including the weighted end 17, causes the return of the parts to normal position.

Referring to Fig. 4, it will be seen that the same construction is illustrated except

that the rod designated 19, in Fig. 3, is now formed of two rods 25, 26, the part 25 carrying the hook 27 which passes through the lock operating lever. The part 26 carries a loop 28, with which the operating rod 46 operates. The rods 25, 26, are connected by the eyes arranged at right angles to each other. It will be seen that because of these eyes, the coupler is permitted a wide range 10 of radial movement, and that the eyes will not interfere with the operation of the coupler lever when required.

Referring to Figs. 5 and 6, it will be seen that the construction is very similar to that 15 heretofore described except that the application is made to a passenger car. In that case the coupler is supported at its front end by a carry-iron 29, suitably secured to the underframing 30 of the passenger car. 20 In this construction I provide brackets 31 on each side of the car, these brackets supporting rods 32, 33, the rods in turn being connected to the loops 34, 35, respectively, formed in the longitudinally extending rod 36. The rod 36 is supported at its rear end 25 in a bracket 37, secured to the underframing of the car.

By reference to Figs. 3, 4, 6, 7 and 8, it will be seen that I provide for longitudinal 30 movement of the coupler under draft without altering the relation of the operating rod thereto by extending the rods through the holding brackets a distance equal to or 35 greater than the longitudinal movement of the coupler, then offsetting the end of the rod to form a retainer as at 39 in Fig. 6. However in connection with this provision, care must be taken that the freedom of 40 movement allowed the rod will not result in the unhooking of the rod from the lock-operating lever. I provide against this in the construction of Figs. 1-4, by bulging a portion 14^a of the coupler head, whereby an 45 abutment is formed. In this construction it will be seen that the rod 19 cannot project forward far enough to allow the hook 18 to become disengaged from the lever 15. In Figs. 5 and 6 I secure this result by the use of a washer 36^a and a cotter 36^b. In Figs. 50 7 and 8 this possibility is overcome by forming a hook or offset 48^a in the rod 48. Referring to Figs. 7 and 8, it will be seen that herein the application is made to a coupler adapted for considerable radial movement. 55 In this case the coupler is supported at its forward end by means of eyes 40, having hooks 41, which coöperate with the flanges of an arc-shaped I-beam 42. The rear end of the coupler is housed in a casting 43, 60 which casting contains a draft rigging and is pivoted at 44, to the car body bolster.

The operating rod in this case is supported at its rear end by a bracket 45, attached to the casting 43. The operating rod 46 is connected to the loop 47 of the rod 48. The 65 rod 48, at its forward end may pass through an opening in one of the yokes 40 and from thence is bent upward, passing through the operating lever 49. It will be seen that in this construction the operating mechanism 70 moves naturally with the coupler and that therefore there is no possibility of the coupler becoming unlocked due to radial motion and the consequent shifting of the operating lever. 75

It will be obvious that I may employ the eye-bolt construction as shown in Fig. 4 in this form also, if desired. Also that various other modifications may be made all without departing from the spirit of my invention. 80

I claim:

1. Coupler operating mechanism comprising, in combination, a car coupler having a lock operating lever, a rod connected to 85 said lever and extending rearwardly in line with said coupler to a point close to the pivotal point of the coupler, means for supporting said rod, means for rotating said rod around its longitudinal axis, said last 90 means including a second rod extending to the side of the car, substantially as described.

2. Coupler operating means comprising, 95 in combination, a car coupler mounted for limited radial movement, an operating lever for said coupler, a rod connected to said lever and extending rearwardly longitudinally of the coupler, said rod having a lever projecting therefrom at a point close to its 100 rear end and a second rod attached to said lever and extending to the side of the car whereby said first rod may be caused to rotate, substantially as described.

3. Coupler operating mechanism comprising, 105 in combination, a car coupler having an operating lever, a rod attached to said lever, said rod extending rearwardly longitudinally of said coupler, a bracket adapted to support the rear end of said rod, said rod 110 having a loop formed therein which loop serves as a lever, and a second rod attached to said first rod at the loop therein, said second rod extending to the side of the car and being adapted to cause limited rotation 115 of said first rod and said coupler operating lever, substantially as described.

EDMUND P. KINNE.
